[57] CLAIM

The ornamental design for a multiple level chess board, as shown and described.

DESCRIPTION

FIG. 1 is a perspective view of a multiple level chess board showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a perspective view of a multiple level chess board showing another embodiment of my new design.

Fig. 7.

Fig. 1.

*Fig. 2.**Fig. 5.*

Fig. 6.
